W. B. ALLISON

DISK WHEEL STRUCTURE

Filed Sept. 29, 1920

INVENTOR.
Walter B. Allison
BY *Sergey M. Webster*
ATTORNEY

UNITED STATES PATENT OFFICE.

WALTER B. ALLISON, OF BUFFALO, NEW YORK, ASSIGNOR TO HARVEY RIM AND WHEEL COMPANY, INC., OF BUFFALO, NEW YORK.

DISK WHEEL STRUCTURE.

Application filed September 29, 1920. Serial No. 413,474.

To all whom it may concern:

Be it known that I, WALTER B. ALLISON, a citizen of the United States, residing at Buffalo, county of Erie, State of New York, have invented certain new and useful Improvements in Disk Wheel Structures; and I do declare the following to be a full, clear, and exact description of the same, reference being had to the accompanying drawings, 10 and to the characters of reference marked thereon, which form a part of this application.

This invention relates to improvements in vehicle wheel construction, and particularly 15 to automobile wheels, the principal object being to apply disks as arranged and shown in application for Patent, No. 282,935, filed March 15th, 1919, to the standard hub and rim provided with wire spokes.

20 A further object is to secure the disks and wheel-parts together so as to provide a rigid structure, and without the use of bolts or rivets of any kind, thus not only improving the appearance of the wheel, but reducing 25 the expense of manufacture.

It is especially proposed to apply the disks to the wire wheels when the latter are turned in to be made over, or the spokes have been damaged by accident, thus enabling the 30 main parts of the wheel—the hub and rim—to be used over again without the expense of installing new spokes, the old ones of which are of course first removed before applying the disks.

35 These objects I accomplish by means of such structure and relative arrangement of parts as will fully appear by a perusal of the following specification and claims.

The figure on the drawings is a sectional view of the wheel.

Referring now more particularly to the characters of reference on the drawings, the numeral 1 denotes a standard wire-wheel hub and 2 the standard rim provided there- 45 with.

The hub comprises a sleeve or spool 3, the outer end of which flares out slightly and is then curled inwardly as at 4. At the inner end of the hub sleeve is an enlarged ring 5 for the reception of the axle flange, which is commonly provided with driving lugs arranged to fit in orifices 6 provided in the wall 7 which connects the ring 5 with the sleeve 3. The edge of the ring 5 opposite

said wall are formed with an outwardly projecting and curved beading as at 8.

The rim 2 comprises a ring 9, the outer edge of which is curled inwardly and then outwardly to form an enlarged beading as at 10, so that a smooth rounded surface is presented. The inner edge of the rim is provided with an outwardly projecting flange 11.

To these parts I attach disks, preferably three in number, there being an outer disk 12, an intermediate disk 13, and an inner disk 14.

The intermediate disk 13 is mounted first, and adjacent its outer periphery is pressed or corrugated outwardly as at 15 to fit the 70 curvature of the beading 10 of the rim, to which it is welded, while at its inner edge said disk is bent to fit inside the ring 5, as at 16, to which ring it is likewise welded. This disk extends from the outer edge of the rim 75 to the inner end of the hub.

The outer disk 12 may then be attached, this disk being bent at its outer edge to fit over the outer edge of the disk 13, and also at its inner edge to conform to the curvature of the portion 4 of the hub, to which portion the disk is welded. The outer disk is preferably convexly curved, while the intermediate disk is oppositely curved, this feature adding to the strength of the wheel 85 and enabling the disks to be made thin and light.

The inner disk 14 which is substantially flat, is attached to the outer surface of the rim flange 10 by being welded thereto, as at 90 17, while its inner edge is bent to fit in the ring 5 but to lay over the similar portion of the disk 13, to which portion it is welded.

From the foregoing description it will be readily seen that I have produced such a 95 device as substantially fulfills the objects of the invention as set forth herein.

While this specification sets forth in detail the present and preferred construction of the device, still in practice such deviations from such detail may be resorted to and do not form a departure from the spirit of the invention, as defined by the appended claims.

Having thus described my invention, what 105 I claim as new and useful and desire to secure by Letters Patent is:

1. In a disk wheel structure comprising

with the standard rim and hub of the wire-spoke type wheel, an inner disk extending between the inner edges of the rim and hub, said disk being welded to the vertical rim-
5 edge and being bent into the hub around said inner edge and being welded thereto, and an outer disk having an outwardly projecting flange following the contour of and lying against the hub and being welded
10 thereto, said outer disk adjacent its other periphery being fixed to the corresponding rim-edge.

2. A disk wheel structure comprising with the standard rim and hub of the wire-spoke
15 type wheel, an inner disk extending between the inner edges of the rim and hub, said disk

being welded to the vertical rim-edge and being bent into the hub around said inner edge, an intermediate disk engaging and being welded to the inner face and edge of the 20 outer side of the rim and extending to and into the hub at the inner end thereof and being welded thereto, the adjacent and overlapping portion of the inner disk being welded to the intermediate disk, and an 25 outer disk extending from the outer end of the hub and being welded thereto, to the outer side of the rim, overlapping the intermediate disk thereat and being welded to said intermediate disk.

In testimony whereof I affix my signature.
WALTER B. ALLISON.
